OF D 13.014

DESIGN FOR A SETTEE-FRAME.

Design No. 13,014, dated June 27, 1882.

UNITED STATES PATENT OFFICE.

AUSBORN F. OLD, OF PHILADELPHIA, PENNSYLVANIA, ASSIGNOR TO
BAKER, PRATT & CO., OF NEW YORK, N. Y.

DESIGN FOR A SETTEE-FRAME.

SPECIFICATION forming part of Design No. 13,014, dated June 27, 1882.

Application filed March 23, 1882. Term of patent 7 years.

To all whom it may concern:

Be it known that I, AUSBORN F. OLD, a citizen of the United States, residing in the city and county of Philadelphia, State of Pennsylvania, have invented and produced a new and original Design for Settee-Frames, of which the following is a specification, reference being had to the accompanying photographic illustration, forming part thereof.

10 A represents a settee-frame having a post, *a*, two arches, *b*, and a bar, *c*. The post rises from said bar, which latter extends transversely, and is connected to the legs *d d'*, and the inner abutments thereof join the post *a*, thus

15 forming two Gothic windows, *e e*.

The ornamentation shown above the arches *b* is not the subject of the present invention. *f* represents a cross-bar, which joins the legs *d d'*, and has open panels *g*. In the rear leg, *d'*, is an open panel, *h*.

20 I claim—

The design for a settee-frame, having legs *d d'*, the two arches *b b*, post *a*, and bar *c*, forming two Gothic windows, *e e*, substantially as set forth.

AUSBORN F. OLD.
